ATTORNEY.

UNITED STATES PATENT OFFICE.

HOMER A. SMITH, OF OAKLAND, CALIFORNIA.

DESIGN FOR AN ELECTROLIER.

No. 39,121.

Specification for Design.

Patented Feb. 11, 1908.

Application filed September 20, 1907. Serial No. 393,866. Term of patent 3½ years.

To all whom it may concern:

Be it known that I, HOMER A. SMITH, a citizen of the United States, residing at Oakland, county of Alameda, and State of California, have invented a new, original, and ornamental Design for Electroliers, of which the following is a specification, reference being had to the accompanying drawing, forming part thereof.

The figure is a side view of an electrolier showing my new design.

I claim:

The ornamental design for an electrolier as shown.

HOMER A. SMITH.
